UNITED STATES PATENT OFFICE.

WILLIAM LOVE, OF McCONNELLSVILLE, OHIO.

IMPROVEMENT IN GAITERS.

Specification forming part of Letters Patent No. 139,321, dated May 27, 1873; application filed April 1, 1873.

To all whom it may concern:

Be it known that I, Wm. Love, of McConnellsburg, in the county of Morgan and State of Ohio, have invented a new and Improved Shoe or Gaiter; and I hereby declare the following to be a full, clear, and exact description thereof, reference being had to the accompanying drawings making part of this specification, in which—

Figure 1 is a side elevation of the shoe.

The object of my invention is to provide a gaiter or shoe which will be easy to the foot, and at the same time avoid uneven wear upon the elastic gore inserted in the sides of it. My invention consists in making the elastic gores slightly tapering, and placing them forward of the projection of the ankle-bone on each side.

In order that those skilled in the art may make and use my invention, I shall proceed to describe the manner in which I have carried it out.

In the said drawings, A is the vamp of the shoe, and B the quarter, which are sewed together along the seams *a b*. About half-way between the seams and the line of the front of the vamp I cut out a portion of it, substantially in the shape shown, and insert an elas-

tic gore, D, reaching about down to the bend in the crimped vamp. Then I insert the piece of leather C between the quarter and gore. By this means the elastic gore is thrown forward of the ankle-bone, and does not press upon any prominent part of the foot, and is not uncomfortable. This also prevents the gore wearing unevenly, as invariably it does when placed over the ankle-bone.

From the drawing it will be perceived that I make my elastic sufficiently wide at its lowest point, and throughout its whole length, to secure ample elasticity around the ankle-bone, and aid the crimped vamp to give a neat and comfortable fit. The leather I leave between the two elastic strips fits against the front of the ankle and leg, and catches the wear, and thus protects the elastic from injury.

Having thus described my invention, what I claim as new, and desire to secure by Letters Patent, is—

A shoe or gaiter, made substantially as described, with the elastic gores inserted forward of the ankle-bone.

WILLIAM LOVE.
